UNITED STATES PATENT OFFICE.

ANTON FODOR, OF VIENNA, AUSTRIA-HUNGARY, ASSIGNOR OF ONE-HALF
TO NICOLAS DE SZEMERE, OF BUDAPEST, AUSTRIA-HUNGARY.

RAILWAY-CAR COUPLING.

No. 797,508.

Specification of Letters Patent.

Patented Aug. 15, 1905.

Application filed February 27, 1905. Serial No. 247,604.

To all whom it may concern:

Be it known that I, ANTON FODOR, a subject of the Emperor of Austria-Hungary, residing at No. 90 Eugengasse, Vienna, Austria-Hungary, have invented new and useful Improvements in Railway-Car Couplings, of which the following is a specification.

This invention relates to an improved constructional form of the arrangement (protected by United States Patent No. 779,472) for tightening the engaged coupling and for automatically untightening the latter when disengaged by means of an eccentric, in which arrangement the movement of the eccentric which tightens the coupling is effected by lever mechanism, whereby both parts are firmly united and the automatic untightening is caused by a weighted lever acting on the shaft instead of by unreliable springs, as heretofore, said weighted lever being raised when tensioned and secured in this position by a tumbler which is automatically released when disengaging the coupling, and thus produces the automatic untightening.

Referring to the accompanying drawings, Figures 1 and 2 show the improved tightening and untightening means in plan and elevation of a coupling, and Fig. 3 shows a part of the same in front elevation.

According to the present invention the shaft 27 is fixed beneath the buffer-plate 19 and can be turned at will by the lever 39, Fig. 1, which is attached to the ends of the shaft and adapted to be placed beneath the buffer-plate 19 when not used. The shaft 27 carries a two-armed lever 40 instead of the spring-barrel and looped lever of United States Patent No. 779,472. The shorter arm of this lever 40 is connected by a rod 41 to the eccentric-lever 18 of the eccentric 17, while the longer arm is weighted by a weight 42, Fig. 2, which replaces the spring of the known construction. The hub of the lever 40 is provided with projections 43, and a horizontal tumbler 45, Fig. 3, which is attached to the buffer-plate 19 and tensioned against the projections 43 by a spring 44, is arranged above the projections in such a manner that when the lever 40 is turned into the tightened position (indicated in Fig. 2 by dot-

ted lines) the said tumbler engages in one of the projections 43, and thus locks the lever 40 in the tightened position.

The spring-drum 20, adapted for the uncoupling and connected to the uncoupling-lever 12 by the chain 22, is loosely and rotatably mounted on a vertical pivot 46 (instead of being keyed to the horizontal coupling-shaft, as heretofore,) and for the purpose of uncoupling it can be turned in the direction of the arrow by means of lever mechanism 47 48, fixed beneath the buffer-plate and shown in Fig. 1 in dotted lines. The spring-drum 20 is provided on its periphery with a cam 49, in the path of which the free end of the tumbler 45 projects, so that when the drum 20 turns in the direction of the arrow, Fig. 1, into the uncoupling position the cam 49 lifts the tumbler 45, which thus releases the lever 40. The latter turns under the action of the weight 42 into the position shown in Fig. 1, and thereby untightens the coupling.

Having now particularly described and ascertained the nature of my said invention and in what manner the same is to be performed, I declare that what I claim, and wish to secure by Letters Patent, is—

In eccentric-actuated tightening and automatically-untightening means for automatic railway-car couplings, the combination of a shaft, a two-armed lever mounted thereon, a weight on one end of said lever, an eccentric, a lever 18 connected thereto, a rod connecting the other arm of the two-armed lever to said lever 18, projections on said two-armed lever, a tumbler engaging with said projections to lock the two-armed lever against movement, a spring-drum having a cam on its periphery and means for rotating said drum to bring the cam in engagement with the tumbler to unlock the parts, substantially as described.

In testimony whereof I have signed my name to this specification in the presence of two subscribing witnesses.

ANTON FODOR.
